UNITED STATES PATENT OFFICE.

HARRY J. BURR, OF NEW HARTFORD, NEW YORK, ASSIGNOR TO THE POSTCRAFT COMPANY, INC., OF UTICA, NEW YORK, A CORPORATION OF NEW YORK.

STAMP-AFFIXING MACHINE.

1,406,535.

Specification of Letters Patent. Patented Feb. 14, 1922.

Application filed August 19, 1920. Serial No. 404,646.

To all whom it may concern:

Be it known that I, HARRY J. BURR, a citizen of the United States, and resident of New Hartford, in the county of Oneida 5 and State of New York, have invented a new and useful Improvement in Stamp-Affixing Machines, of which the following is a specification.

This invention consists in a stamp affixing machine in which the leading stamp of 10 a ribbon is folded back, moistened, separated and affixed as the machine is operated.

The object of this invention is to provide certain improvements in the construction, 15 form, arrangement and operation of the several parts whereby the structure is materially simplified and the accuracy of operation is ensured.

This invention is more particularly directed to improvements of the machine disclosed in United States Letters Patent No. 1239624, dated September 11, 1917, and in my application filed May 17, 1918, Serial 20 No. 235165.

25 A practical embodiment of my invention is represented in the accompanying drawings, in which,

Fig. 1 represents a perspective view of the machine.

30 Fig. 2 represents a front view with the front door removed.

Fig. 3 represents a section taken in the plane of the line III—III of Fig. 2.

Fig. 4 represents a section on an enlarged 35 scale, taken in the plane of the line IV—IV of Fig. 2.

Figs. 5, 6, 7 and 8 represent front views 40 with the door removed, the parts being shown in the positions which they assume as the handle is depressed to different positions.

Figs. 9 and 10 represent front views with the door and certain other parts removed 45 to illustrate the position of the frame plate just before and just after it has been released from the handle at the limit of its depressed movement.

Fig. 11 represents a section on an enlarged scale, taken in the plane of the line 50 XI—XI of Fig. 6.

Fig. 12 represents a perspective view of the drum and the parts carried thereby.

Fig. 13 represents a perspective view of

the drum plate and the parts carried thereby.

55 The casing 1 is provided with a front door 2, which door is preferably provided with a transparent window whereby the action of the parts within the casing may be observed. This casing is provided with an opening 3 through its bottom. A frame plate 4 has a limited vertical sliding movement between retaining guides 5 and 6 fixed to the back wall of the casing. A stud shaft 7 extends forwardly from the frame 60 plate 4 and on this shaft there is loosely mounted the sleeve 8 of a rocking cam lever 65 9 which coacts with an abutment 10 upris- ing from the bottom of the casing 1, for con- trolling the relative vertical movement of 70 the frame plate with respect to the casing as will hereinafter appear.

The operating handle 11 has its shank 12 75 slidable through the top of the casing 1, the lower end of which shank is secured to the forwardly turned upper end 13 of a slide 14 located within the casing between the back and the frame plate 4, in the present instance, in a shallow groove 15 formed in the back of the casing. This slide 14 is 80 provided with a forwardly extended stud 16 which travels in a vertical groove 17 in the frame plate 4. The forwardly turned upper end 13 of this slide 14 travels in a vertical groove 18 in the upper end of the 85 frame plate.

The stamp drum comprises the back wall 19 and the cylindrical side wall 20, which drum has a hub 21 which is loosely mounted on the sleeve 8. The side wall 20 of the 90 drum is divided to form a slot 22 through which the stamp ribbon passes. Adjacent to the slot 22 the drum is provided with a presser foot 23.

A drum plate 24 is loosely mounted on the 95 hub 21 of the drum in close proximity to the back wall 19 of the drum, which plate is pro- vided with two forwardly extended arms 25, 26, over and under which the stamp ribbon passes on its way to the exterior of the drum. 100 A curved spring arm 27 is secured at one end to the under face of the forwardly extended arm 25 of the drum plate, the free end of the arm extending around and in close prox- imity to the side wall 20 of the drum, across 105 the slot 22 and through an inwardly turned

rib 28 of the side wall. This spring 27 presses the stamp ribbon against the forwardly projecting arm 26 of the drum plate 24.

5 The back wall 19 of the drum is provided with an elongated slot 29 into which the stud 16 on the slide 14 projects.

A stamp severing knife 30 is located in front of and normally against the front end 10 of the presser foot 23, which knife forms the lateral extension of a lever 31, pivoted at 32 to the back wall 19 of the drum. This lever is provided with an off-set portion 33 which has a limited movement in a slot 34 15 in the back wall of the drum.

A helical spring 35 surrounds the hub 21 of the drum, one end of which spring passes through a slot 36 in the drum plate 24 and a slot 37 in the back wall of the drum into 20 engagement with the knife lever 31. The other end of this helical spring is seated in a kerf 38 in the end of the sleeve 8, and a wider kerf 39 in the end of the stud shaft 7, thereby permitting the sleeve 8 and its cam 25 lever 9 a limited rocking movement under spring tension. The swinging movement of the rocking cam lever 9 against the tension of the helical spring 35 is obtained by the engagement of a stud 109 on the lever with a 30 cam surface 114 at the lower end of the slide 14, which cam surface leads to a slot 214 for receiving the said stud 109.

A folding lever 40 for folding over the leading stamp of the ribbon on the return 35 movement of the drum is pivoted at 41 to the back wall of the drum, the outer end 42 of which lever is turned laterally across the drum in front of the knife 30. The inner arm 43 of this lever is provided with a cam 40 surface 44 arranged to engage a stud 45 which projects forwardly from the frame plate 4, said cam surface 44 terminating in a hook 46 for swinging the folding lever as the drum is oscillated.

45 This stud 45 projects forwardly through an elongated concentric slot 47 in the back wall into an elongated concentric slot 48 in the drum plate 24. The drum plate 24 is provided with a latch lever 49 pivoted at 50, which latch lever is fitted to travel back and forth in the slot 47 of the drum. This latch lever is provided with a nose 51 on its inner edge which is adapted to be brought into and out of the notch 52 in the inner wall of the 55 slot 47.

The width of the slot 48 is the same as the diameter of the stud 45, but the slot 47 is considerably wider so that when the latch lever 49 locks the drum plate 24 to the drum 60 by the entrance of the nose 51 into the notch 52, the stud 45 may pass between the outer edge of the latch lever 49 and the outer edge of the slot 47. When the nose 51 of the lever 49 is forced out of its notch 52 it will hold 65 the stud 45 at one end of the slot 48.

A stamp moistening reservoir 53 is carried by the lower end of a lever 54, pivoted at 55 to the back of the casing, a spring 56 serving to normally hold the reservoir at the limit of its outward movement away from 70 the drum.

This moistening lever is operated from the handle 11 as follows:—

A cam dog 57 is mounted to have both lateral and swinging movements on the stud 75 58 which projects upwardly from the drum plate 4. A spring 59 serves to yieldingly hold the dog at the limit of its lateral movement against the drum plate 4. The body of the dog is bent to form a cam 60 and a 80 double cam surface 61 is formed along the inner edge of the dog. The forwardly turned upper end 13 of the handle slide 14 is provided with a recess 62 through which the cam surface 61 of the dog passes 85 on the upward movement of the handle, the dog being swung backwardly to swing the moistening reservoir inwardly during the downward movement of the handle by the engagement of the cam surface 61 of the dog 90 with the adjacent edge of the forwardly turned upper end 13 of the plate 14 at the side of the recess 62.

The reservoir 53 is provided with a stamp moistening device such as a wick 63 and it is 95 also provided with a suitable water inlet 64 which passes through an elongated slot 65 in the back of the casing.

The means for ensuring the full downward or backward movement of the handle 100 to complete the cycle of operations of the machine when once started, is as follows:—

A double pawl 66 is pivoted at 67 to the back of the frame plate 4, which pawl is located within a vertical slot 68 in the handle slide 14 in position to engage the teeth of a rack 69 along one side of the slot. A 105 spring 70 serves to hold the double pawl yieldingly in engagement with the rack.

The top wall of the slot 68 has a cam surface 71 arranged to engage the pawl to throw it over to one position when the slide is depressed to the limit of its movement and the bottom wall of the said slot has a cam surface 72 arranged to engage the pawl and 110 throw it over to its other position when the slide is raised to the limit of its upward movement, the spring 70 acting to yieldingly hold the pawl in either of its operative positions.

The stamp ribbon is clamped to and released from the drum at different points in the movement of the drum by the following means:—

A clamping lever 73 is mounted on a pin 125 74 projecting forwardly from the back wall of the drum. This lever is provided with a nose 75 which travels along the periphery of the drum plate 24 into and out of a notch 76 in said periphery. A spring 77 tends to 130

swing the nose 75 of the clamping lever inwardly and the ribbon clamping surface of the said lever outwardly. It will be understood that the roll of stamps 78 is mounted 5 on the movable core 79, which surrounds the spring 35. The ribbon leading from this roll passes between the arm 25 and the side wall 20 of the drum. From thence it leads between the arm 26 and spring 27. From 10 thence it leads between the clamping lever 73 and the side wall of the drum. After it leaves this point it passes outwardly through the slot 22 in the side wall of the drum, underneath the knife 30 and over the laterally turned arm 42 of the folding lever. 15

The operation of the machine is as follows:—

Let it be supposed that the parts are in their normal position, as shown in Fig. 2, 20 with the leading stamp of the ribbon folded back over the knife by the outward movement of the folding lever. The machine is placed upon the article to which the stamp is to be affixed and the handle 22 is depressed to the limit of its downward movement. During this downward movement the following conditions obtain:

As the handle is started on its downward movement, the drum will be rocked forwardly by the engagement of the slide stud 16 with the wall of the slot 29 in the back wall of the drum to move the drum against the tension of the helical spring 35. As the drum rocks in this forward direction, the 35 cam surface 44 of the folding lever will be engaged by the stud 45, carried by the frame slide 4, for swinging the laterally turned outer end 42 of this lever inwardly snugly against the side wall of the drum in front 40 of the stamp severing knife 30. It will be noted that the drum plate 24 is held against rotary movement by the raising of the latch lever 49 to partly close the slot 48. It will also be noted that the stamp ribbon clamping lever 73 is held out of its clamping engagement with the ribbon. The positions which the parts assume up to this time are indicated in Fig. 5. The further downward movement of the handle and its slide 50 will rock the drum still further in its forward direction, taking the stamp ribbon with it and causing the back of the folded over leading stamp to be wiped across the wick 63 of the moistening device, the moistening reservoir having been swung inwardly by the outward movement of the cam dog 57, due to the engagement of its cam surface 61 with the forwardly extended upper end 13 of the handle slide. In the 55 meantime the nose 75 of the clamping lever 73 has been brought opposite to the notch 76 in the drum plate, thus bringing the clamping surface of the said lever into position to clamp the stamp ribbon against the 60 side wall of the drum. In the meantime the

nose 51 of the latch lever 49 has been brought opposite to the notch 52 in the inner wall of the elongated slot 47. The positions of the parts as above described are shown in Fig. 6.

The further downward movement of the handle and its slide will rock the drum still further forwardly to bring the parts to the position shown in Fig. 7 with the moistened turned over stamp located between the article to which the stamp is to be affixed and the 75 presser foot 23. In this movement, the drum and drum plate are moved together as the latch lever 49 has been forced inwardly by the stud 45 to bring the nose 51 of the latch lever into the notch 52, thus permitting the 80 stud 45 to travel along both the slots 47 and 48 in the drum and drum plate respectively. In the meantime the moistening device has been permitted to be swung outwardly out of the way. With the parts in this position 85 a portion of the elongated slot 29 is brought into a substantially vertical position with the stud 16 about to enter the vertical portion of the slot.

The further slight downward movement 90 of the handle and its slide will cause the cam lever stud 109 to be engaged by the slide cam surface 114 to swing the cam lever 9 against the tension of the helical spring 35, out of its locking engagement with the abutment 10 on the bottom of the casing and thus 95 permit the bodily downward movement of the drum and drum plate together with the parts carried thereby, with respect to the casing, whereby the moistening stamp is 100 pressed firmly against the article to which it is to be affixed. It will be noted that this slight downward movement has brought the slide stud 16 into engagement with the knife lever 31 and has swung the knife lever 105 against the tension of the helical spring 35 to move the knife 30 a short distance away from the presser foot 23 sufficiently to sever the affixed stamp from the ribbon. This final downward movement of the handle and 110 its slide will also cause the double pawl 66 which has been locking the handle slide against upward movement, to be engaged by the cam surface 71 to throw the pawl over into the position to release the slide to permit the helical spring 35 to return the parts to their normal position. The positions of the parts at the limit of the downward movement of the handle are shown in Fig. 8.

As the downward pressure on the handle 115 is removed, the first operation will be the slight upward movement of the handle, the frame plate and the drum as well as the return of the knife 30 to its position against the front end of the presser foot 23. The 120 cam lever 9 is also permitted to be swung back into its locking position with the abutment 10 under the tension of the helical spring 35. The further upward movement 125 of the handle will permit the reverse rock- 130

ing movement of the drum, the stamp ribbon being moved with the drum by the clamping lever 73 until the stud 45 reaches the front end of the slot 48 when the reverse 5 rocking movement of the drum plate is stopped. The further reverse movement of the drum will swing the nose of the clamping lever out of its notch 76 in the drum plate to release the stamp ribbon, and it will also 10 swing the nose 51 of the latch lever 49 out of its notch 52 in the drum to lock the stud 45 to the drum plate. This reverse movement of the drum with the stamp ribbon released will cause the next succeeding stamp 15 of the ribbon to be exposed beyond the presser foot and knife with a slight over-feed. As the drum approaches the limit of its reverse rocking movement, the laterally turned upper end 42 of the folding lever 20 will be swung upwardly by the engagement of the stud 45 with the hooked end of the cam surface 44 of the said lever, thus folding the exposed stamp back over the knife into the position shown in Fig. 2. 25 This slight over-feed of the stamp ribbon as the parts return to their normal positions ensures the accurate folding over of the stamp along its separation line and the proper engagement of the knife 30 in the 30 apex of the folded over portion in the next succeeding operation of the machine. During the return movement of the parts as above described, the cam dog 57 which 35 controls the movement of the stamp moistening device will, because of its shape and laterally yielding movement ride through the recess 62 in the forwardly turned upper end 13 of the slide without rocking the dog and swinging the moistening device. 40 It is to be understood that during the first part of the downward movement of the handle, the drum will move forwardly along the ribbon until the knife 30 enters the apex of the fold between the ribbon and folded 45 over stamp, when the ribbon will be moved thereafter with the drum by the knife until clamped by the clamping lever 73 as hereinbefore described. 50 It will also be observed that as the handle and slide reach the limit of their upward movement, the cam surface 72 of the slot 68 in the slide 14 will engage the double pawl 66 (which has been locking the slide against downward movement until it has completed 55 its upward movement), to throw the cam over to its original position to lock the handle against upward movement once it has been started on its downward movement. This ensures the complete movement of the 60 parts in either direction. 65 While this machine is described as a stamp affixing machine, it is obvious that it may be used for affixing gummed labels of any character in ribbon form. 65 It is obvious that various changes may be

made in the construction, form and arrangement of the several parts without departing from the spirit and scope of my invention; hence I do not wish to limit myself to the particular embodiment herein shown, but, 70

What I claim is:—

1. In a machine of the character described, a drum adapted to contain a series of stamps in ribbon form, an independently movable drum plate, a drum supporting frame, a stamp folding lever pivoted on the drum, means for controlling the movement of the lever and drum plate as the drum is oscillated, and means for oscillating the drum. 75

2. In a machine of the character described, a drum adapted to contain a series of stamps in ribbon form, an independently movable drum plate, a drum supporting frame, a stamp folding lever pivoted on the drum, and a stud fixed on the frame for controlling 80 the movement of the lever and drum plate as the drum is oscillated, and means for oscillating the drum. 85

3. In a machine of the character described, a drum adapted to contain a series of stamps in ribbon form, an independently movable drum plate, a drum supporting frame, a stamp folding lever pivoted on the drum and having a cam surface, a stud fixed on the frame engaging said cam surface for controlling 90 the movement of the lever as the frame is oscillated, said stud serving to control the movement of the drum plate, and means for oscillating the drum. 95

4. In a machine of the character described, a drum adapted to contain a series of stamps in ribbon form, an independently movable drum plate, a drum supporting frame, a stamp folding lever pivoted on the drum and having a cam surface terminating at one end 100 in a hook, and a stud fixed on the frame arranged to engage said cam surface and hook for controlling the movement of the lever as the drum is oscillated, said stud also serving to control the movement of the drum 105 plate, and means for oscillating the drum. 110

5. In a machine of the character described, a drum having a stamp ribbon feeding slot, an independently movable drum plate, a ribbon clamping lever carried by the drum 115 and controlled by the drum plate, means for locking the drum plate to and releasing it from the drum, and means for rocking the drum and for effecting the affixing of a stamp. 120

6. In a machine of the character described, a drum adapted to contain a series of stamps in ribbon form, devices carried by the drum arranged to over-feed the ribbon as the drum rocks backwardly and to take up the 125 over-feed and thereafter advance the ribbon with the drum as the drum rocks forwardly, and means for rocking the drum.

7. In a machine of the character described, a drum adapted to contain a series of stamps 130

in ribbon form, devices carried by the drum arranged to over-feed the ribbon and to fold back the leading stamp thereon as the drum rocks backwardly and to take up the over-feed and thereafter advance the ribbon with the drum as the drum rocks forwardly, and means for rocking the drum.

8. In a machine of the character described, a drum adapted to contain a series of stamps 10 in ribbon form, means carried by the drum arranged to over-feed the ribbon and to fold back the leading stamp as the drum rocks backwardly, and means on the drum to take up the over-feed and enter the apex of the 15 angle formed by the folded back stamp, and to thereafter advance the ribbon with the drum as the drum rocks forwardly, and means for rocking the drum.

9. In a machine of the character described, 20 a frame, a rotatable drum mounted thereon having a stamp ribbon feeding slot, an independently movable drum plate, a clamping lever within the drum controlled by said drum plate to clamp the stamp ribbon to and release it from the drum as the drum rocks forwardly and backwardly, and means for rocking the drum and for effecting the affixing of a stamp.

10. In a machine of the character described, 30 a vertically movable handle slide, a vertically movable frame plate, a rotatable stamp drum, a rotatable drum plate loosely mounted in the drum, the movements of said drum and drum plate being controlled by the 35 handle slide and frame plate, and means for effecting the affixing of a stamp.

11. In a machine of the character described, 40 a vertically movable handle slide, a vertically movable frame plate, a rotatable stamp drum, a rotatable drum plate loosely mounted in the drum, means for locking the drum plate to and releasing it from the drum, the movements of the said drum and drum plate being controlled by the handle 45 slide and frame plate, and means for effecting the affixing of a stamp.

12. In a machine of the character described, 50 a vertically movable handle slide, a vertically movable frame plate, a rotatable stamp drum, a rotatable drum plate loosely mounted in the drum, said handle slide and frame plate having studs for controlling the movements of the drum and drum plate, and means for effecting the affixing of a stamp.

55 13. In a machine of the character described, a vertically movable handle slide, a vertically movable frame plate, a rotatable stamp drum, a rotatable drum plate loosely mounted in the drum, means for locking the 60 drum plate to and releasing it from the drum, said handle slide and frame plate having studs for controlling the movements of the drum and drum plate, and means for effecting the affixing of a stamp.

65 14. In a machine of the character de-

scribed, a vertically movable handle slide, a vertically movable frame plate having a forwardly extended shaft, a stamp drum and a drum plate both rotatably mounted on said shaft, said handle slide and frame 70 plate having studs for controlling the movements of the drum and drum plate, and means for effecting the affixing of a stamp.

15. In a machine of the character described, a vertically movable handle slide, 75 a vertically movable frame plate having a forwardly extended shaft, a stamp drum and a drum plate both rotatably mounted on said shaft, means for locking the drum plate to and releasing it from the drum, 80 said handle slide and frame plate having studs for controlling the movements of the drum and drum plate, and means for effecting the affixing of a stamp.

16. In a machine of the character described, 85 a vertically movable handle slide, a vertically movable frame plate having a forwardly extended shaft, a stamp drum having a hub rotatably mounted on said shaft, a drum plate rotatably mounted on said hub, said handle slide and frame plate having studs for controlling the movements of the drum and drum plate, and means for effecting the affixing of a stamp.

17. In a machine of the character described, 95 a vertically movable handle slide, a vertically movable frame plate having a forwardly extended shaft, a stamp drum having a hub rotatably mounted on said shaft, a drum plate rotatably mounted 100 on said hub, means for locking the drum plate to and releasing it from the drum, said handle slide and frame plate having studs for controlling the movements of the drum and drum plate, and means for effecting the affixing of a stamp.

18. In a machine of the character described, 105 a vertically movable handle slide, a vertically movable frame plate having a forwardly extended shaft, a stamp drum 110 and a drum plate both rotatably mounted on said shaft, said handle slide and frame plate having studs for controlling the movements of the drum and drum plate, said drum having a stamp ribbon slot, a lever carried 115 by the drum for clamping and releasing the stamp ribbon, said lever being under the control of the drum plate, and means for effecting the affixing of a stamp.

19. In a machine of the character described, 120 a vertically movable frame plate having a forwardly extended shaft, a stamp drum and a drum plate both rotatably mounted on said shaft, means for locking the drum plate to and releasing it from the drum, said handle slide and frame plate having studs for controlling the movements of the drum and drum plate, said drum having a stamp ribbon slot, a lever carried 125 by the drum for clamping and releasing the 130 stamp ribbon, and means for effecting the affixing of a stamp.

stamp ribbon, said lever being under the control of the drum plate, and means for effecting the affixing of a stamp.

20. In a machine of the character described, a vertically movable handle slide, a vertically movable frame plate having a forwardly extended shaft, a stamp drum and a drum plate both rotatably mounted on said shaft, said handle slide and frame plate having studs for controlling the movements of the drum and drum plate, said drum having a stamp ribbon slot therethrough, a lever carried by the drum for clamping and releasing the stamp ribbon, said lever being under the control of the drum plate, said drum plate having forwardly extended arms and a curved spring arm secured at one end to one plate arm for pressing the stamp ribbon against the other arm, and means for effecting the affixing of a stamp.

21. In a machine of the character de-

scribed, a vertically movable handle slide, a vertically movable frame plate having a forwardly extended shaft, a stamp drum and a drum plate both rotatably mounted 25 on said shaft, means for locking the drum plate to and releasing it from the drum, said handle slide and frame plate having studs for controlling the movements of the drum and drum plate, said drum having a stamp 30 ribbon slot for clamping and releasing the stamp ribbon, said lever being under the control of the drum plate, said drum plate having forwardly extended arms and a curved spring arm secured at one end to one 35 plate arm for pressing the stamp ribbon against the other arm, and means for effecting the affixing of a stamp.

In testimony, that I claim the foregoing as my invention, I have signed my name this 40
17th day of August, 1920.

HARRY J. BURR
